UNITED STATES PATENT OFFICE

DAVID T. WADSWORTH, OF COLD SPRINGS, KENTUCKY, ASSIGNOR TO THE WADSWORTH ELECTRIC MANUFACTURING COMPANY, OF COVINGTON, KENTUCKY, A CORPORATION OF KENTUCKY

INCLOSED ELECTRIC SWITCH

Application filed March 17, 1928. Serial No. 262,419.

My invention relates to externally operated switch and fuse boxes, and particularly to novel devices for locking and preventing theft of current therefrom.

5 In my co-pending application, Serial No. 732,272, filed August 15, 1924, I have disclosed a switch and fuse box having a rocking arm which may be manually moved from outside the box. The box has a switch in 10 one part of the box and fuses in a separate compartment in another. A lid is provided for the fuse compartment which may be opened only when the rocking arm is in off position. Thus, it is impossible for a person to be shocked while replacing a fuse for 15 the lid to the fuse compartment cannot be opened unless the switch is off. Further, the switch cannot be closed when the cover for the fuse compartment is open.

20 It is the object of my invention, as will be hereinafter disclosed, to provide, particularly in combination with this type of box, for a locking member which will effectively prevent theft of current when the main cover to 25 the box is locked. Since the switch is operable by a rocking arm exteriorly of the box, the novel locking device must lock this arm so that it cannot be jammed closed. Another object is the provision of a locking device 30 which may be readily moved into locking position. A still further object is the incorporation in one integral member for a movable part which will serve the double function of preventing access to the fuse box when the switch is in "on" position and of permanently locking the actuating handle for the switch, when the box is locked to prevent theft of 35 current.

The above and other objects to which reference will be made in the ensuing disclosure I accomplish by that certain combination and arrangement of parts of which I have shown a preferred embodiment.

Referring to the drawings:

40 Figure 1 is a plan view of the switch and fuse box with the main cover open.

Figure 2 is a sectional view of the box taken along the lines 2—2 in Figure 1.

45 Figure 3 is a sectional view of the box taken along the lines 3—3 in Figure 1.

Figure 4 is a similarly taken sectional view with the locking member in position to block the movement of the operating handle.

Figure 5 is a perspective view of the blocking and locking member.

The switch box consists of a metal case 1 having a hinged lid 2. The box has a plate 3 attached to it which has a hole 4 which registers with the hole 5 in a latch member 6 which is pivoted to the outer side of the cover. When the cover or lid is closed on the case the extension or plate 3 extends through a slot 7 in the cover. The fuse compartment is indicated at 8 and a lid 9 is mounted slidably on the cover in channel strips 10 so that the lid may be moved to close the fuse compartment unless otherwise blocked.

The switch is mounted on a porcelain block 11 and operates in the obvious manner. A bail 12 extends across within the case, being 70 pivotally mounted in the sides of the case as indicated at 13. The bail engages a switch contact member 14 which is pivotally mounted as indicated at 14a.

None of the structure described hereinbefore forms any part of my invention as the subject matter of the switch box combination is described in my co-pending application.

One of the side walls of the case has channels 15 which slidably retain the blocking 75 and locking member generally indicated at 16. This member has flanged edges 17 which are retained within the channels 15. At the top of the member there is a projection 18 which, when the bail is in the lowered 80 position, as indicated in Figure 1, will abut the end of the cover 9 and prevent access to the fuse compartment. In Figure 3 the handle with which the switch is turned is shown 85 in the position in which the switch is open. In this position the bail is in the upper end of the slot 19 so that the ledge 18 of the sliding member is below the plane of the cover and the fuse compartment will be accessible.

The sliding member has a slot 20 which 90 permits the member to be elevated far enough in the channels to permit the bail to slide along the bottom 21 of the member until it seats in the slot 22. With the bail seated within the slot 22 the handle cannot be turned, 95 100

the fuse compartment will be locked shut, the switch will be off, and if a padlock is inserted within the aligned holes 4 and 5 the whole box will be so locked that it will be impossible for an unauthorized person to steal current.

It is of importance that the sliding member should serve a double function of locking both the bail and fuse compartment cover, for otherwise an unauthorized person might tamper with the fuse compartment when the box was locked, as for example, when the tenant of a house moved out and the company providing electricity did not wish to remove the fuse box, as a new tenant was expected shortly.

Modifications in the particular construction which I have disclosed will readily occur to those skilled in the art, but insofar as others utilize the principle of my device with no more than mechanical modifications, I consider that such modifications will be within the scope of my invention.

Having thus described my invention, what I claim as new and desire to secure by Letters Patent, is:—

1. In an electric switch and fuse box, having a switch, a rocking bail for actuating said switch, with a handle for said bail extending outside the box, and a fuse compartment with a cover therefor, means controlled by the operation of the bail for blocking the opening of said cover, said means further providing means for blocking the movement of said bail and for locking the bail in a second selected position.

2. In a switch and fuse box having a switch, a fuse compartment with means to provide access thereto, and means for opening and closing the switch therein, means for inhibiting the operation of said first mentioned means controlled by the movement of said second mentioned means, said last named means further providing means for blocking the operation of said second mentioned means and for locking the bail in a second selected position.

3. In a switch and fuse box having a switch, a fuse compartment with a closing lid therefor, and a bail movable from outside the box for opening and closing the switch, means controlled by the position of said bail for blocking the closing lid, said means having a position of movement in which said bail will also be blocked and for locking the bail in a second selected position.

4. In a switch and fuse box having a switch, a fuse compartment with a closing lid therefor, and a bail movable from outside the box for opening and closing the switch, means controlled by the position of said bail for blocking the closing lid, said means having a position of movement in which said bail will also be blocked, said means comprising an integral member having a curved slot therein with a slot which allows the bail

to be removed from said slot, said member having a notch therein in which said bail may be engaged.

5. In a switch and fuse box having a fuse compartment with a closing lid therefor, and a switch with a bail movable from outside the box for closing the switch, means for blocking both the lid and bail comprising a slotted member slidably mounted within said box.

6. An electric switch and fuse box comprising a switch, a member for operating the switch comprising a rocking part controlled from outside the box, said box having an opening and a closing lid therefor, a slide in the box, means for slidably mounting the slide, said slide being formed and located so as to block the opening of said lid when said slide is in selected position, means on the slide detachably engaging the rocking part but normally allowing rocking movement thereof, said slide being further provided with means for blocking the movement of said rocking part.
